RAILWAY CAR CONSTRUCTION

Original Filed Nov. 3, 1924 3 Sheets-Sheet 3

Patented Aug. 13, 1929.

UNITED STATES PATENT OFFICE.

WILLIAM W. BLAKELY, OF DEXTER, MICHIGAN.

RAILWAY-CAR CONSTRUCTION.

Application filed November 3, 1924, Serial No. 747,664. Renewed July 30, 1927.

My invention relates to improvements in railway cars, designed for the carrying of freight or bulk.

An important object of the invention is to provide a railway car of the above mentioned character, with means for receiving or holding the load in a manner to properly prevent displacement in shipment, which means is built into or preferably permanently attached to the car, throughout the major portion of its length, thereby properly distributing the points of attachment and the stresses.

A further object of the invention is to provide means of the above mentioned character, whereby a suitable number of divisions or compartments may be readily formed in or upon a railway car, for the purpose of receiving the several loads.

20 A further object of the invention is to provide means of the above mentioned character, possessing a large range of adjustment, and which is also foldable or collapsible, to occupy a position out of the way, when it is desired to use the car without divisions or compartments.

A further object of the invention is to provide means of the above mentioned character, which are simple in construction, 30 strong, durable, and comparatively cheap to manufacture.

A further object of the invention is to provide means of the above mentioned character, which may be readily installed within or applied to the ordinary freight railway car, without materially changing its construction.

A further object of the invention is to provide simple and reliable connecting means 40 between the standards and the floor attached member.

A further object of the invention is to provide adjustable means for connecting the uprights or standards with a portion of the car, so that the standards may be made in standard lengths, and may be installed upon cars in use, which may vary slightly in dimensions.

50 A further object of the invention is to provide means of the above mentioned character, embodying parts which may be readily formed from standard steel sections.

A further object of the invention is to provide means of the above mentioned character, which, when in use and not in use, re-

main a permanent part of the car, and hence the expense encountered in returning the special shipping devices to the starting point is dispensed with.

Other objects and advantages of the invention will be apparent during the course of the following description.

In the accompanying drawings, forming a part of this specification, and in which like numerals are employed to designate like parts throughout the same,

Figure 1 is a central vertical longitudinal section through a railway car, embodying my invention,

Figure 2 is a transverse section taken on line 2—2 of Figure 1,

Figure 3 is a detail central longitudinal section through the attaching means for the lower end of the standards or uprights.

Figure 4 is a transverse section through the same,

Figure 5 is a fragmentary plan view of the base rail or attaching element,

Figure 6 is a perspective view of the upper end of one of the standards or uprights, 80 showing the attaching means associated therewith,

Figure 7 is a transverse section through the same,

Figure 8 is a plan view of same, 85

Figure 9 is a perspective view of one of the locking elements for the base of the standards, and

Figure 10 is a vertical sectional view taken through the freight car at a point between the uprights 30 and the adjacent wall 18 of the freight car.

In the drawings, wherein for the purpose of illustration is shown a preferred embodiment of my invention, the numeral 15 designates the body of an ordinary freight railway car, of the box type, which is employed for the purpose of illustration, although the invention is not necessarily restricted to this type of car, as I contemplate embodying the same within or upon a gondola or flat car. This body includes the usual longitudinal beams 16, receiving thereon the usual transverse flooring 17. The body comprises sides 18, ends 19, and a top 20, having transverse beams 21, as is customary.

In accordance with my invention, I employ longitudinal attaching beams 22, extending beneath and adjacent to the beams 21 of the top. These attaching beams prefer-

ably extend throughout substantially the entire length of the interior of the car. These attaching beams are preferably formed of angle irons, being L-shaped. Both webs of these angle irons are provided throughout the entire length with openings 23 and 24, suitably spaced, as shown. The angle irons are attached to the beams 21 by means of bolts or the like passing through the openings 23. The invention is in no sense restricted to this particular form of connection, as the same may have to be varied somewhat, depending upon the construction of the car upon which these attaching beams are applied. The attaching beams 22 are preferably spaced inwardly from the sides 18, as clearly shown in Figure 2, and preferably extend parallel therewith.

I preferably provide longitudinal grooves 25 in the upper surface of the floor planks 17, and these grooves are preferably co-extensive in length with the attaching beams or rails 22, and also preferably disposed in the same vertical longitudinal plane. Arranged above the grooves 25 are base-attaching rails 26, provided with openings 27, for the reception of screws 28, or other attaching elements, which engage in the floor planks 17. Obviously any other suitable means may be employed to securely anchor the base rails to the floor. The base rails are provided preferably throughout substantially their entire length with spaced openings 29, preferably corresponding in number and arrangement with the openings 24 in the vertical webs of the horizontal attaching beams or rails 22. The base rails preferably have their upper faces transversely inclined or curved from their center to their edges, whereby the wheels of a hand truck may be readily rolled over the same. The invention contemplates the use of any suitable number of standards or uprights 30, which are preferably formed of angle irons. These standards are preferably provided throughout substantially their entire length, in their webs, with spaced sets of openings 31 and 32. The openings in one set are preferably staggered with relation to the openings of the other set, and this is provided to enable a larger range of adjustment of the parts by using either web, in a manner to be explained.

Means are provided to connect the lower end or base of each standard with the base rail 26, preferably comprising a pair of attaching elements, including body portions 33, carrying depending reduced extensions 34, the lower ends of which are bent laterally to produce horizontal fingers 35. The body portions 33 have openings 36, for the reception of a bolt 37, to be passed through the opening in the selected web of the standard. As clearly shown in Fig. 3, the web of the standard is positioned between the body

portions 33, and the horizontal extensions or fingers 35 extend in opposite directions and engage beneath the cross-webs of base-rail 26, the necks 34, of course, extending through the openings 29. I have found this manner of attachment to be advantageous, inasmuch as it is strong, durable, reliable and readily detachable, but I wish it understood that the invention is not necessarily restricted to its use, as other means of attachment may be employed.

The means for attaching the upper ends of the standards to the attaching beams or rails 22 will now be described. In connection with each standard 30, I preferably provide an intermediate element or plate 37', which is rigidly secured to the vertical web of the attaching beam or rail 22, by means of bolts 38 passing through the openings 24, and these bolts may carry special rings or washers 39, but this is not essential, since that may be dispensed with, in which event the stiffness of plate 37' will be suitably increased. The intermediate plate 37' is provided with a vertical slot 40, for the reception of a bolt 41, by means of which the upper end of the upright may be clamped to the intermediate plate. The function of this intermediate plate and its slot is to provide an adjustable connection, within limits, between the upper end of the standard and the upper attaching beam or rail. This is preferred, as the height of a box car may vary slightly, and it is desired to make the standards in as few standard lengths as is practical. It will be understood, however, that the standard may be directly clamped to the upper attaching beam or rail, and I contemplate using any suitable means for this purpose.

As illustrative of one of the uses of my invention, attention is now called to Figure 1. In this view I have shown two pairs of standards 30, mounted in place, at selected points. The first pair to the left has transverse planks 42, which are secured to these standards by bolts or the like, passing through the openings in their webs. These planks form a partition which divides off the adjacent end of the car into a compartment or chamber 43, in which any suitable material may be safely shipped, such as furniture, or any other material. I have shown horizontal beams 44, attached to the webs of the standards by bolts 45, and planks 46 may be arranged upon these beams and suitably secured thereto, if necessary. It is thus seen that these planks form, in effect, floors or decks, providing a plurality of superposed chambers or compartments 47, 48 and 49. These chambers have their right ends open, so that material may be stored therein, and these ends may be later closed by planks suitably secured to the standards to prevent shifting, if desired. It is obvious that the

arrangement of the standards and associated elements for producing the various compartments, is susceptible of a large range of adjustment, as may be required under varying conditions.

In Figure 10 I have illustrated the invention as employed in the shipment of an automobile. In this view two pairs of the standards 30 are employed, and I may also 10 arrange horizontal beams 50 in the upper portion of the car and attach them to the standards by bolts 51 or the like. Planks 52 may be secured to the upper edges of these beams and form a compartment or chamber 15 53, for the reception of material to be shipped, and the open end of this compartment may be closed by planks secured to the standards for preventing shifting of the material, if desired. Beneath the floor plat- 20 form is a chamber 54, within which the automobile 55 is stored. This automobile is connected with the standards 30 by means of connecting devices 56, which may be at- 25 tached to the hubs of the wheels and to the standards. These connecting devices pref- 30 erably embody a yielding element 57, which will permit of a slight longitudinal move- 35 ment of the automobile and properly absorb the shocks. The connecting devices 56 will not be described in detail in the present application, as they are not claimed, per se, in this case, but are fully described and claimed 40 in a co-pending application, Serial No. 747, 665, filed the same day with this applica- 45 tion.

It will be seen that when the freight or cargo is removed from the car, that the several partitions may be readily removed and the lower ends of the standards may be dis- 40 connected from the base rails and these lower ends swung upwardly, by first slightly loosening the bolts 41. The free ends of the standards may be secured to the beams or rails 22 by means of bolts. When thus 45 arranged these standards will be entirely out of the way and will not appreciably re- 50 duce the usable cubic capacity of the car. It is thus seen that these standards and as- 55 sociated elements remain a permanent fix- ture to the car; and in the shipment of spe- 60 cial articles, such as automobiles and the like, it is not necessary to return the holding means ordinarily employed for this purpose to the starting point. A great deal of money 65 will thus be saved by the use of my inven- tion.

It is to be understood that the form of my invention, herewith shown and described, is to be taken as a preferred example of the 60 same, and that various changes in the shape, size, and arrangement of parts may be re- 65 sorted to, without departing from the spirit of my invention or the scope of the sub- 70 joined claims.

Having thus described my invention, I 65 claim:

1. The combination with a railway box car, having a floor provided with longitudinal grooves and having a top, of attaching beams extending longitudinally of said top, 70 base rails secured to the floor of the box car over the longitudinal grooves and having spaced openings therein, standards, elements secured to the lower ends of the standards and having lateral projections for engaging 75 beneath the base rails, means for connecting the upper ends of the standards with the attaching beams, and load restraining means co-acting with the standards.

2. The combination with a railway car, of 80 a base rail carried thereby and having spaced openings formed therein, attaching elements having lateral extensions beneath the base rail, a standard to be inserted between the attaching elements, and means connecting 85 the standard with the attaching elements.

3. The combination with a railway box car, of attaching beams arranged in the upper portion thereof, base rails arranged near the bottom thereof, standards connected be- 90 tween the attaching beams and the base rails, generally horizontal beams connected with and supported by the standards, and flooring supported by the generally horizontal beams 95 for producing a plurality of superposed compartments.

4. The combination with a railway box car having a floor and a top, of attaching beams arranged at the top of the box car, base rails arranged on the floor of the box 100 car, standards connected between the attaching beams and the base rails, generally horizontal beams connected with and supported by the standards, partition means carried by the generally horizontal beams for providing a plurality of generally horizontal compartments, and partition means carried by 105 selected standards for providing a generally vertical compartment.

5. The combination with a railway box 110 car having a floor, of attaching beams per- 115 manently mounted in the upper portion thereof, base rails permanently secured to the floor of the box car and having their upper faces transversely inclined so that a truck or the like may be readily driven over the same, standards, means for detachably connecting the standards with the base rails, and means for connecting the standards with the attaching beams.

6. The combination with a railway box car, of attaching beams secured within the upper portion of the box car, base rails se- 120 cured in the lower portion of the box car, standards, each standard having a plurality of faces, each face having a plurality of lon- 125 gitudinally spaced openings, the openings in one set being staggered with relation to the

openings in the other set, means for connecting the lower ends of the standards to the base rails, means for connecting the upper ends of the standards to the attaching beams, 5 and load restraining means adapted to be secured to the standards by bolts or the like passing through said openings.

7. The combination with a railway box car, of attaching beams secured within the 10 upper portion of the box car and having vertical webs provided with spaced openings, intermediate plates associated with the vertical webs and having openings and substantially vertical slots, bolts adapted to pass 15 through the openings of the intermediate plates and selected openings in said vertical webs, standards, bolts carried by the upper ends of the standards and adapted for insertion within the substantially vertical slots, 20 base rails secured within the lower portion of the box car, and means connecting the lower ends of the standards with the base rails.

8. The combination with a box car, of 25 attaching beams secured within the upper portion of the box car and having vertical webs provided with spaced openings, intermediate plates having substantially vertical slots, bolts carried by the intermediate plates 30 and having spacing elements and adapted for insertion within selected openings of the vertical webs whereby the intermediate plates may be clamped to the vertical webs in spaced relation thereto, standards carrying bolts operating within the substantially vertical slots, 35 base rails secured within the lower portion of the box car, means connecting the lower ends of the standards with the base rails, and load supporting means carried by said standards.

9. In a carrier having a floor portion, a 40 rail secured to the floor portion and having a plurality of openings therein, a standard above said floor portion, and an attaching element secured to said standard having a portion projecting through an opening in said rail and terminating in a lateral extension engageable with the under surface of the rail.

10. In a shipping device having a floor 45 portion, a rail secured to said floor portion, a standard having a plurality of longitudinally spaced openings therein for adjustably supporting a load, and an attaching element upon said standard having a projection extending through said rail and having an interlocking engagement therewith.

11. In a shipping device having a floor 50 portion formed with a longitudinal ex-

tending recess, a rail bridging the recess and 60 having a plurality of spaced openings therein, a standard for supporting a load, and an attaching element upon said standard extending through one of the openings aforesaid and having a lateral projection disposed 65 within said recess and engageable with the rail.

12. In a shipping device having spaced attaching plates, a supporting member disposed between said plates and having one 70 end slidably connected to one of said plates, permitting a longitudinal adjustment of said supporting member relative to the last mentioned plate, and an attaching element upon the opposite end of said supporting 75 member having a portion extending through an opening formed in the other of said plates and terminating in a lateral projection arranged to engage the under surface of said plate.

13. In a shipping device having spaced top and bottom walls, a plate secured upon one of said walls having a series of openings therein, a standard extending between said walls, and attaching elements carried 85 by said standard and having lateral projections extending through one of the openings aforesaid and engageable with the under surface of said plate.

14. In a shipping device having spaced 90 attaching plates formed with a plurality of openings therein, a standard disposed between said plates having one end slidably connected to one of said plates, permitting a longitudinal adjustment of said standard 95 relative to the last mentioned plate, and attaching means upon the opposite end of said standard having lateral projections extending through one of the openings formed in the other of said plates and engageable with the under surface of the latter.

15. In a shipping device having spaced 100 walls, a rail secured to one of said walls having a series of openings therein, a plate adjustably secured to said rail, and a standard extending between said walls and adjustably secured to said plate.

16. In a shipping device having spaced 110 walls, plates secured to said walls, a supporting member interposed between said plates and a slidale connection between said supporting member and one of said plates permitting a longitudinal adjustment of said supporting member relative to the last mentioned plate.

In testimony whereof I affix my signature.

WILLIAM W. BLAKELY.
